UNITED STATES PATENT OFFICE.

CHARLES H. NOWACK, OF CHICAGO, ILLINOIS, ASSIGNOR TO AMERICAN CAN COMPANY, OF NEW YORK, N. Y., A CORPORATION OF NEW JERSEY.

CONTAINER.

1,393,815.

Specification of Letters Patent.

Patented Oct. 18, 1921.

Application filed December 21, 1917. Serial No. 208,312.

To all whom it may concern:

Be it known that I, CHARLES H. NOWACK, a subject of the Emperor of Austria-Hungary, residing in Chicago, in the county of 5 Cook and State of Illinois, have invented a new and useful Improvement in Containers, of which the following is a specification.

This invention relates in general to containers and has more particular reference to 10 containers comprising a tight friction cover fitted upon a gasket carried by the body and compressing said gasket against the opposing mouth of the body.

The principal object of the invention is 15 the provision of a hermetically closed friction top container which can be opened readily with the hand and without the necessity of using any pry-off tools or implements or requiring the provision of any 20 opening devices, consisting merely of a one-part body, a one-part cover and an interposed gasket.

A still further object of the invention is 25 the provision of a container of pleasing appearance and economical manufacture.

Other objects and advantages of the invention will be apparent as it is better understood from the following description when considered in connection with the 30 accompanying drawing illustrating a preferred embodiment thereof.

Referring to the drawing:

Figure 1 is a section through a container embodying my present invention.

35 Fig. 2 is a partial enlarged section taken similarly of Fig. 1.

Fig. 3 is an enlarged detail showing the action of the hand in opening the cover.

Figs. 4, 5 and 6 are perspective views 40 showing the cover, gasket and body separated from each other.

For the purpose of illustrating my invention I have shown a flat circular container comprising a body 1 and a cover 2. The body 1 is of the usual cylindrical form and is provided at the top with a curled false wire edge 3. The cover consists merely of a top or flat part 4 and a cylindrical flange 5. The flange 5 is offset above its bottom 50 edge at 6 to engage the bead 3 and a gasket 8 is interposed between the bead or wire edge 3 and rests in the offset part 6. The lower part of the cover flange 9 extends straight down below the bead. The gasket is prefer-

ably positioned in the cover before closing 55 of the box and the box closed by merely pushing the cover tightly over the edge of the body, and the parts are so constructed that the gasket in this action is compressed and a hermetical seal formed. The box 60 may be opened by grasping it as shown on the drawing and pressing in on two opposite sides of the cover. The engaging portions of the top and cover are of different flexibility, with greater flexibility in the cover. 65 The pressure of the fingers produces a slight deformation and the cover springs or snaps off. Indeed the box may be opened if sufficient pressure is exerted at a single point in the depending part 8 of the cover flange. 70

It is thought that the invention and many of its attendant advantages will be better understood from the foregoing description and it will be apparent that various changes may be made in the form, construction and 75 arrangement of the parts without departing from the spirit and scope of the invention or sacrificing any of its material advantages, the form hereinbefore described being merely a preferred embodiment thereof. 80

I claim:

1. The combination of a container body having its top edge formed in an outwardly turned curl, a cover therefor formed with a shoulder adapted to be supported by the 85 top of said curl when the container is closed, the edge of the cover being formed in a vertical flange which depends from the outer part of said shoulder around the outer side of said curl and extends below the bottom 90 of said curl, and a vertically thin gasket arranged between the curl and the said depending flange and against which the flange engages tightly, said cover being disengageable from the body by pressing inwardly 95 against said depending cover flange at a point below said curl of the body.

2. The combination of a container body having its top edge formed in an outwardly turned curl, a cover therefor formed with a 100 shoulder adapted to be supported by the top of said curl when the container is closed, the edge of the cover being formed in a vertical flange which depends from the outer part of said shoulder around the outer side 105 of said curl and extends below the bottom of said curl, and a vertically thin gasket arranged between the curl and the said de-

pending flange and against which the flange engages tightly, the depending flange and body curl being of such relative flexibility and stiffness that pressure on the flange in an inward direction toward the middle of the container will spring the cover from the body.

Signed in the presence of two subscribing witnesses.

CHARLES H. NOWACK.
